Attorney

UNITED STATES PATENT OFFICE.

JOHN W. CURRY, OF KANE, PENNSYLVANIA.

PACKAGE-TIE.

1,227,394.

Specification of Letters Patent. Patented May 22, 1917.

Application filed April 4, 1916. Serial No. 88,981.

To all whom it may concern:

Be it known that I, JOHN W. CURRY, a citizen of the United States, residing at Kane, in the county of McKean and State 5 of Pennsylvania, have invented certain new and useful Improvements in Package-Ties, of which the following is a specification.

The present invention relates to cord and rope holders and more particularly to new 10 and useful improvements in package ties.

An object of my invention is to provide a simple and cheaply constructed package tie which will securely bind a package when used in conjunction with any suitable flexible 15 tying element such as a cord string or the like.

Another object of my invention is to provide a device of the class described formed preferably of a single strand of wire having 20 means associated therewith for connection with a tying element such as a cord string or the like, said device being formed with cord gripping means whereby to engage the free ends of the cord when wound 25 a number of times about a package or the like.

A further object of my invention is to provide a package tying device of the class described so constructed as to readily adapt 30 itself to various contingencies, thereby facilitating the application of the device to a package or the like.

Other objects and advantages to be derived from the use of my improved package 35 tie will appear from the following detail description and the claims, taken with an inspection of the accompanying drawing, in which—

Figure 1 is a perspective view of a package, showing the preferred form of package tie applied thereto, embodying the improvements of my invention,

Fig. 2 is a plan view of the preferred 40 form of package tie,

Fig. 3 is a side elevational view of the base plate, being shown in section,

Fig. 4 is a perspective view of a modified 45 form of my invention,

Fig. 5 is a perspective view of the wire 50 gripping element and the preferred form of my invention,

Fig. 6 is a still further modified form of 55 my invention, and

Fig. 7 is a perspective view of another 60 modified form of my invention.

Referring more particularly to the draw-

ings, wherein similar characters of reference 60 designate like and corresponding parts throughout the various views, and specifically referring to the preferred form of my invention shown in Figs. 1 to 3, I provide a package tie formed of a single strand of wire designated 1 in its entirety, and a loop 65 as at 2 intermediate its ends. The loop portion forms two parallel portions 3, said parallel portions being bent upon themselves as at 4 to provide inherently resilient arms 5 in spaced relation to the portions 3, said arms 5 being inclined bent upon themselves as at 6, to provide a spaced writing or directing portion 7, the free ends of the strand being looped to form eyes 8. The eyes 8 form directing or guiding means for amply inserting or facilitating the insertion of a flexible tying element in a manner herein- 70 after set forth in detail.

In order to prevent the package tie from rolling over when in use on a package I provide a base portion formed of a pair of plates 9 and 10. The plates 9 and 10 overlap 75 the portion 3 of the package tie, and are welded together at their free ends. This structure is best shown in Fig. 1, this also being shown in a modified form of my invention illustrated in Fig. 4 described in detail hereinafter.

The manner of placing a tying element 80 about a package is best shown in Fig. 1, the preferred form of my invention being herein shown in view. The package is designated 11, and the tying element is designated 12, having one end thereof connected 85 to the loop 2, the intermediate portion of said tying element being wound tight about the package, the intersections of said loop 90 about the package being designated 13. The free ends 14 of the tying element 12 is engaged between the portions 3 and 5 of the package tie and is then looped upon themselves to be directed between the eyes 8. 95 The tying elements are now brought rearwardly toward the center portions 5. Pulling 100 forwardly on the free ends of the tying element will bind securely between the portions 5.

Referring to Fig. 4 in which the modified 105 form of my invention is shown, the wire strand 15 is provided with the looped portions 16, gripping portions 17 and guiding eyes 18. The base plates are designated 19 and are formed intimately with the plate 110 shown in Figs. 1 to 3. In using this form of

my invention the tying element is placed between the portions 17 and 15 and looped upon itself and drawn between the eyes 18 and portions 17 whereby securely binding 5 said tying element against accidental displacement.

Referring to Fig. 6 I have provided a modified form of my invention wherein a strand of wire is looped as at 20 to form an eye for 10 engagement with a tying element, said strand being formed with wing portions 21, the arms thereof being twisted as at 22 and bent upon themselves as at 23 forming spaced divergent spring arms 24 formed 15 with eyes 25 on the free ends thereof. The tying element is secured to this form of my invention similarly to the form of my invention illustrated in Fig. 4, the distinguishing feature being the integral formation of 20 the wings 21 to prevent overturning of the tying element when used or when being tied.

Referring to the further modified form of my invention illustrated in Fig. 7 I have provided a strand of wire formed with a 25 loop or eye 26, said strand being formed with wings 27 and 28, the portions of the strands forming the wings being looped about themselves as at 29 and 30 and adjacent the loop 26 and extending outwardly as 30 at 31 and bent upon themselves as at 32, and terminating in spring arms 33 provided with guiding or directing eyes 34. This form of my invention is used similarly to the forms of my invention illustrated in Figs. 4 35 and 6, the distinguished feature being the peculiar arrangement of the strand of wire adjacent the looped portion whereby a strong and durable wire structure is provided.

40 It will readily be apparent to those skilled in the art that I have provided a new and improved package tie which is simple in construction and cheap to manufacture and which may be readily and quickly applied to 45 any package. I do not limit myself to any particular form of the tie shown in the drawings however, I do lay particular stress upon the specific formation of the arm gripping the tying element. This gripping feature insures against possible disconnection 50

of the tying element from the tie. The feature of my invention wherein the base plate 9 prevents overturning of the tying device during a tying operation is a feature of the invention upon which I also lay particular 55 stress.

From the above description taken in connection with the accompanying drawing, it is thought that a clear and comprehensive understanding of the construction, operation and advantages of my invention may be had, and while I have shown and described my invention as embodying a specific structure, I desire that it be understood that I may make such changes on said structure as do not depart from the spirit and scope of the invention as claimed.

What I claim as new and desire to secure by Letters-Patent is:—

1. A package tie formed from a single 70 strand of wire having a looped portion intermediate the ends thereof to provide an eye for engagement with the tying element, the said ends extending in diametrically opposite directions after crossing each 75 other, wing members formed by bending the said ends to prevent over-turning of the package tie, the free ends thereof being twisted and then bent upon themselves to form a pair of divergent spring arms 80 opposite the said eye portion, eyes formed on the free ends of the said arms to provide a guiding and gripping means for a flexible tying element whereby to guide the tying element into the gripping position. 85

2. A package tie of the class described including a strand of wire having a looped portion intermediate the ends thereof to provide an eye for engagement with the tying element, wing portions associated with 90 said wire adjacent the loop to prevent the tie from over-turning, the free ends of said wire being intimately associated in parallel spaced relation and bent back upon themselves, and eyes formed on the extremities 95 of said ends whereby the tying element may be guided into a gripping position.

In testimony whereof I affix my signature hereto.

JOHN W. CURRY.
